FLORAL RACK

Clarence J. White, Peoria, Ill.

Application November 7, 1950, Serial No. 12,867

Term of patent 14 years

(Cl. D35—3)

To all whom it may concern:

Be it known that I, Clarence J. White, a citizen of the United States, residing at Peoria, in the county of Peoria, State of Illinois, have invented a new, original, and ornamental Design for a Floral Rack, of which the following is a specification, reference being had to the accompanying drawing, forming a part hereof.

Fig. 1 is a front perspective view of a floral rack, showing my new design; and

Fig. 2 is an enlarged fragmentary view of a portion of one of the vertical rails thereof.

The dominant features of my design reside in the portions shown in full lines.

I claim:

The ornamental design for a floral rack, as shown and described.

CLARENCE J. WHITE.
